UNITED STATES PATENT OFFICE.

FRANK W. RIESENBERG, OF CHICAGO, ILLINOIS.

WRENCH.

1,081,700.

Specification of Letters Patent. Patented Dec. 16, 1913.

Application filed April 24, 1913. Serial No. 763,277.

To all whom it may concern:

Be it known that I, FRANK W. RIESENBERG, a citizen of the United States, and a resident of the city of Chicago, county of Cook, and State of Illinois, have invented certain new and useful Improvements in Wrenches, of which the following is a specification.

My invention relates to wrenches and 10 more particularly to the chain-tong types.

The object of this improvement is to provide a device of this character which will be of simple construction and efficient in operation.

15 The invention consists in the combinations and arrangements of parts hereinafter described and claimed.

The invention will be best understood by reference to the accompanying drawing 20 forming a part of this specification, and in which—

Figure 1 is a side view of a wrench embodying my invention, Fig. 2 is a central section of the handle, jaw and a portion of 25 the chain used in the device, and Fig. 3 is a section taken on line 3—3 of Fig. 1.

The preferred form of construction as illustrated in the drawing comprises a jaw 4 having a serrated curved face 5 on one 30 side and a serrated straight face 6 on its other. The face 6 of the jaw 4 is provided with a groove 7 extending the length of the jaw. In the groove 7 at one end of the jaw 4 is secured a chain 8 one link of which 35 is pivoted to said jaw as at 9. At the other end of jaw 4 also pivoted in groove 7 as at 10 is a handle 11. Said handle 11 is provided with a recess 12 in one side thereof adapted to receive the constricted portions 40 of the links 8. The lever 11 is adapted to swing on the pivotal point 10 in the slot 7 of the jaw 4 to accommodate different sizes of the article 14 which it is desired to turn. Articles of larger sizes are preferably operated on by face 5 of said jaw as the movement of the lever 11 is limited by means of the connecting portion between the sides of said jaw 4 at the face 5. The face 6 of jaw 4 is especially adapted for turning objects 45 of smaller sizes since the handle 11 is free to swing in the groove 7 into face 6.

In operation, the jaw 4 is placed in contact with an article 14 which it is desired to turn and chain 8 placed around said article with the constricted portion 13 of one of 55 the links of said chain inserted in the recess 12 of said handle. The chain is drawn tightly by the operator around article 14, and the constricted portion of that link which comes nearest to the link 8 is placed 60 in said recess to lock the chain therein. Then upon moving the handle in the direction of the arrow 15 in Fig. 1, it will be observed that operation of the device will be effected by binding the jaw 4 tightly against 65 article 14. The device is preferably made in small sizes for household use.

While I have illustrated and described the preferred form of construction for carrying my invention into effect, this is 70 capable of variation and modification without departing from the spirit of the invention. I, therefore, do not wish to be limited to the precise details of construction set forth, but desire to avail myself of 75 such variations and modifications as come within the scope of the appended claim.

Having described my invention what I claim as new and desire to secure by Letters Patent is:

80 A wrench comprising a jaw having a groove in one of its faces; a chain pivoted in one end of said groove to said jaw, each link of said chain having a central constricted portion; a handle pivoted in the other end of said groove to said jaw, said handle having a lateral recess substantially perpendicular thereto in one side extending to a depth corresponding to the width of said chain, the sides of said recess being 85 adapted to conform to and snugly fit the constricted portions of said links, substantially as described.

90 In testimony whereof I have signed my name to this specification in the presence of 95 two subscribing witnesses.

FRANK W. RIESENBERG.
